UNITED STATES PATENT OFFICE.

KARL WINKLER, OF JERSEY CITY, NEW JERSEY.

BRISTLE-FEEDING ATTACHMENT FOR BRUSH-MAKING MACHINES.

1,074,399.

Specification of Letters Patent. Patented Sept. 30, 1913.

Application filed May 1, 1913. Serial No. 764,763.

To all whom it may concern:

Be it known that I, KARL WINKLER, a citizen of the German Empire, residing in Jersey City, in the county of Hudson and State of New Jersey, have invented certain new and useful Improvements in Bristle-Feeding Attachments for Brush-Making Machines, of which the following is a specification.

10 This invention relates to bristle-feeding attachments for brush-making machines by which the bristles, fibers or other material are formed into tufts of uniform size and supplied in a reliable manner to the tuft-filling devices, so as to be inserted into the holes bored into the brush-backs.

15 The object of this invention is to provide a bristle-feeding attachment in which the supply of bristles or fibers for the brush-tufts can be kept up continuously without stopping the machine, and by which the necessary number of tufts of uniform size is formed and supplied to the brush-back filling devices, whatever be the speed at which 20 25 the brush-making machine is operated, so that a greatly increased output of the brush-making machine is rendered possible and an even and uninterrupted working of the same secured.

30 The invention consists of a bristle-feeding attachment for brush-making machines which comprises a bristle-box having means for guiding the bristles, an endless longitudinally-grooved feed-band in said box, a correspondingly-grooved presser-roller near the feed-end of the band, a driving-roller for said band, a bristle-receptacle above the driving-roller and presser-roller provided with clearers extending into the center-groove of the band and groove of the presser-roller respectively, and a horizontally-reciprocating slide-plate guided on the bristle-receptacle and having a transverse groove at its underside for taking up a uniform quantity of bristles and forming a tuft at each forward motion of the slide-plate.

35 The invention consists further of certain details of construction and combinations of parts which will be fully described herein-after and finally pointed out in the claims.

40 In the accompanying drawings, Figure 1 represents a side-elevation of my improved bristle-feeding attachment for brush-making machines; Fig. 2 is an end-elevation taken from the left-hand side of Fig. 1, Fig.

3 is a vertical transverse section on line 3—3, Fig. 1, drawn on a larger scale, Fig. 4 is a plan-view of the machine, Fig. 5 is a detail vertical section through the left-hand end 60 of the feed-box and the bristle-supply receptacle taken on line 5—5, Fig. 2, and Fig. 6 is a detail vertical section through the feed-band and driving-roller, showing the clearer for stripping the bristles from the 65 feed-band.

Similar letters of reference indicate corresponding parts throughout the different figures of the drawings.

Referring to the drawings, *a* represents 70 a bristle-feed box, which is made of oblong shape and which is supported in proper position relatively to the tuft-filling devices of the brush-making machine so as to deliver the tufts of bristles formed by the attachment directly to said filling devices. 75

In the bristle-feed box *a* is arranged an endless longitudinal feed-band *b*, which is driven in the direction of the arrow shown in Fig. 1, by a driving-roller *b*¹ at one end 80 and guided by a guide-roller *b*² at the opposite end of the feed-box. The required quantity of bristles, fibers or other material, which is used for the tufts of the brushes, is inserted from time to time into the feed-box 85 either by hand or supplied from a suitable hopper, as shown in dotted lines in Fig. 1. The feed-band *b* is held tight by means of a guide-roller *b*³ below the driving-roller *b*¹, which guide-roller acts on the lower part of 90 the feed-band, while the upper part of the feed-band is acted upon by a rotary presser-roller *d*. The upper horizontal portion of the feed-band is supported on a longitudinal bar *b*⁴. The endless band *b* is provided with 95 a center-groove *b*⁵, while the presser-roller *d* is provided with a center-groove *d*¹, which is in register with the center-groove of the feed-band. The bristles are fed in forward direction by the feed-band and guided by a 100 longitudinal guide-piece *c*, which is adjusted on the feed-box by means of slotted straps *c*¹ and set-screws *c*², as shown in Fig. 4. A second bristle guide-piece may be arranged at the opposite side of the feed-band, though 105 one guide-piece is sufficient for most purposes, so as to give a certain play to the opposite ends of the bristles in being moved forward by the feed-band. The bristles are fed forward by the feed-band and passed 110 between the same and the presser-roller *d* into a bristle-receptacle *f*, which is arranged

vertically above the driving-roller b^1 and presser-roller d . The end-walls f^1 of the bristle-receptacle f are provided with clearers f^2 which extend respectively into the longitudinal groove of the feed-band b and into the circumferential groove of the presser-roller d , as shown clearly in Fig. 5, said clearers serving for stripping the bristles off the feed-band and presser-roller and permitting them to be conducted in upward direction into the bristle-receptacle f . The side-walls f^3 of the bristle-receptacle f are adjustable for the length of the bristles by horizontal shanks f^4 which pass through the upwardly-extending side-walls of the bristle-feed box a , and which are provided at their outer ends with knobs or handles f^5 for permitting the adjustment to the length of the bristles fed into the bristle-box. At the upper end of the bristle-receptacle f is supported on a bracket g^1 a horizontal guide-plate g^2 , on which is guided a reciprocating slide-plate g which is provided in its underside with a transverse groove g^3 which, in passing over the upper end of the bristle-receptacle and the horizontal guide-plate g^2 , is filled with bristles from the body of bristles which is pressed in upward direction in the bristle-receptacle by the feed-band and presser-roller so as to form a tuft which is delivered over the guide-plate to the filling devices of the brush-making machine. The slide-plate g is guided in a guide-box g^4 on top of the bristle-receptacle f , said guide-box having an oiler o , and the slide-plate is actuated by means of a lever g^5 , which engages by its slotted end the rear-end of the slide-plate and transmits reciprocating motion to the slide-plate by the oscillating motion imparted to the lever in any suitable manner.

Longitudinal forward feeding motion is imparted to the feed-band b and its driving-roller b^1 by a belt-and-pulley transmission from an overhead shaft first to the pulley-shaft s and then by a worm w on the pulley-shaft and a worm gear-wheel w^1 to an intermediate shaft s^1 . The shaft s^1 is arranged at right angles to the pulley-shaft s and transmits by gear-wheels w^2 , w^3 rotary motion to the shaft s^2 of the driving-roller b^1 of the feed-band, as shown in Fig. 4. The presser-roller d is rotated by the shaft s^1 which passes transversely through the feed-box a . Between the hub of the gear-wheel w^2 and a boss w^4 on the inner side-wall of the bristle-feed box a is interposed a ball-bearing h , while a second ball-bearing h^1 is interposed between the hub of the worm gear-wheel w^1 and the hub h^2 of a short hollow shaft s^2 which turns in bearings of a standard h^3 . A friction-disk h^4 keyed to the shaft s^1 presses on a yielding disk h^5 in a recess in the hub of the worm gear-wheel w^1 while the outer tapering end

of the hub h^2 is acted upon by the toe-piece h^6 of a fulcrumed and weighted lever h^7 . When too great a quantity of bristles is fed into the bristle-receptacle f , the pressure in the same becomes too great and the rotary motion imparted to the driving-roller b^1 is retarded by the free turning of the worm gear-wheel w^1 between the ball-bearing h and the friction-disk h^4 , so that the transmission of motion by the gear-wheels w^2 , w^3 to the driving-roller and feed-band is interrupted. By this arrangement the regular supply of bristles to the bristle-receptacle and to the tuft-forming slide-plate is retarded or entirely discontinued until the overpressure of the bristles in the bristle-receptacle is relieved by the action of the slide-plate and the regular feed motion of the bristles resumed. The reciprocating motion of the slide-plate, which has to supply from 100 to 120 tufts per minute, is thereby regularly and automatically kept up without any danger of interruption by overpressure on the bristles in the bristle-receptacle. The bristles are of sufficient length to permit their doubling up into tufts for being inserted into the socket-holes of the brush-back by the filling devices of the brush-making machine. As the weight h^8 of the counterbalanced pressure-lever h^7 is adjusted for a certain amount of pressure in the bristle-box, it is obvious that as soon as this pressure is reached, the rotary motion of the presser-roller is interrupted by the interposed friction devices on the shaft s^1 , while the proper supply of bristles to the bristle-receptacle is automatically restored as soon as the overpressure in the same is relieved by the action of the slide-plate g . By this arrangement the automatic continuous and reliable feeding of the bristles to the tuft-forming groove of the slide-plate and the uniform formation and supply of tufts to the filling devices of the brush-making machine is secured.

As the supply of bristles to the open or supply end of the bristle-box can be readily kept up from time to time by supplying a new quantity of bristles, and as the feeding of the bristles to the bristle-receptacle and reciprocating slide-plate is kept up uniformly, a full, regular and continuous supply of tufts of bristles to the bristle-filling devices of the brush-making machines is obtained, so that the brush-making machine can be kept running to its full capacity with a continuous and full supply of tufts for filling the brush-backs in the machine.

I claim:

1. A bristle-feeding attachment for brush-making machines, comprising a bristle-feed box, an endless feed-band in the same, means for imparting forward motion to the feed-band, a presser-roller at the feed-end of the feed-band, a bristle-receptacle located above

the feed-end of the feed-band and presser-roller, and a horizontally-reciprocating slide-plate having a transverse tuft-forming groove moving over the upper end of the bristle-receptacle.

2. A bristle-feeding attachment for brush-making machines, comprising a bristle-feed box, a longitudinal endless feed-band in the same, means for guiding the bristles in said feed-box, means for imparting forward motion to said feed-band, a presser-roller adjacent to the feed-end of the feed-band, a bristle-receptacle above the feed-end of the feed-band and the presser-roller, adjustable end-walls for said bristle-receptacle, and a horizontally-reciprocating slide-plate having a transverse tuft-forming groove moving over the upper end of the bristle-receptacle.

3. A bristle-feeding attachment for brush-making machines, comprising a bristle-feed box, a longitudinally-grooved endless feed-band in the same, means for imparting forward motion to the feed-band, a circumferentially-grooved presser-roller at the feed-end of the feed-band, a bristle-receptacle above the feed-end of the feed-band and the presser-roller, and provided with clearers extending into the longitudinal groove of the feed-band and circumferential groove of the presser-roller, and a horizontally-reciprocating slide-plate having a transverse tuft-forming groove and moving over the upper end of the bristle-receptacle.

4. A bristle-feeding attachment for brush-making machines, comprising a bristle-feed box, a longitudinally-grooved endless feed-band in the same, a driving-roller for imparting forward motion to the feed-band, guide-rollers below said driving-roller and at the opposite end of the feed-band, a rotary pressure-roller adjacent to the driving-roller, a bristle-receptacle above the driving and pressure rollers, adjustable end-walls in said receptacle, a horizontally-reciprocating

slide-plate above the upper end of the bristle-receptacle and having a transverse tuft-forming groove, and a guide-box for said slide-plate.

5. A bristle-feeding attachment for brush-making machines, comprising a bristle-feed box, an endless feed-band in the same, driving means for imparting forward motion to the feed-band, a presser-roller at the feed-end of the feed-band, a bristle-receptacle located above the feed-end of the feed-band and presser-roller, a horizontally-reciprocating slide-plate having a transverse tuft-forming groove and moving over the upper end of the bristle-receptacle, and a friction device interposed in the driving means of the feed-band for retarding or interrupting the supply of bristles to the bristle-receptacle in case of overpressure in the same.

6. A bristle-feeding attachment for brush-making machines, comprising a bristle-feed box, an endless feed-band in the same, a rotary driving-roller for imparting forward motion to the feed-band, a presser-roller at the feed-end of the feed-band, a bristle-receptacle located above the feed-end of the feed-band and the presser-roller, a horizontally-reciprocating slide-plate having a transverse tuft-forming groove moving over the upper end of the bristle-receptacle, a worm-gear interposed between the driving-shaft and the shaft of the presser-roller, a friction-clutch acting on the worm-gear, and a fulcrumed and weighted lever acting on the shaft of the worm-gear for interrupting the motion of the driving-roller and the supply of bristles to the bristle-receptacle in case of overpressure in the same.

In testimony, that I claim the foregoing as my invention, I have signed my name in presence of two subscribing witnesses:

KARL WINKLER.
